(57) **CLAIM**

The ornamental design for a cold room interior latch, as shown and described.

DESCRIPTION

FIG. 1 is a perspective view of a cold room interior latch showing our new design.

FIG. 2 is a top view thereof.

FIG. 3 is a bottom view thereof.

FIG. 4 is a front view thereof.

FIG. 5 is a rear view thereof; and,

FIG. 6 is a left side view thereof, the right side view being a mirror image thereof.

The broken lines depict portions of the cold room interior latch that form no part of the claimed design.
